GRINDING WHEEL FEEDING MECHANISM

Herbert A. Silven, Worcester, Mass., assignor to
 Norton Company, Worcester, Mass., a corpora-
 tion of Massachusetts

Application June 5, 1940, Serial No. 338,967

2 Claims. (Cl. 51—95)

The invention relates to grinding machines, and more particularly to a hydraulically operated grinding wheel feeding mechanism.

One object of the invention is to provide a simple and thoroughly practical, hydraulically operated grinding wheel feeding mechanism. Another object of the invention is to provide a suitable wheel feeding mechanism so that the in-feeding movement of the grinding wheel may be precisely controlled to grind successive work pieces to a predetermined size. Another object of the invention is to provide a backlash eliminating mechanism whereby the operating parts of the feeding mechanism are always maintained with a pressure in one direction.

A further object of the invention is to provide a fluid pressure operated mechanism for maintaining a predetermined pressure on the wheel slide in one direction so that the thrust of the feeding mechanism parts is always in positive control of the wheel feeding movement. A further object of the invention is to provide a hydraulic piston and cylinder mechanism which applies a predetermined pressure on the wheel slide in one direction so as to pick up the lost motion of the feeding mechanism parts to facilitate precise duplication of parts in production grinding. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is an end elevation of a grinding machine, having parts broken away and shown in section to illustrate the improved wheel feeding mechanism together with a hydraulic piping and wiring diagram, and

Fig. 2 is a fragmentary cross-sectional view, on an enlarged scale, of the hydraulic wheel slide actuating mechanism.

A grinding machine has been illustrated in the drawing comprising a base 10 which supports a transversely movable wheel slide 11 which is mounted on transversely extending ways (not shown) on the base 10. The wheel slide 11 supports a rotatable grinding wheel 12 which is mounted on one end of a rotatable wheel spindle 13. The wheel spindle 13 may be driven by any

well known mechanism, such as by means of a pulley 14 mounted on the other end of the wheel spindle 13 which is connected by means of a driving belt 15 with a suitable source of power, such as an overhead drive shaft or the like.

The base 10 also supports a longitudinally traversable work supporting table 18 which is arranged to be traversed longitudinally relative to the base 10 on a flat way 19 and a V-way 20. The table 18 is provided with a rotatable work support including a headstock 21 and a footstock (not shown), each of which is provided with work supporting centers rotatably to support a work piece 22 in operative relation with the grinding wheel 12. The longitudinally movable table 18 may be traversed longitudinally by a manually operable traverse mechanism including a manually operable traverse wheel 25 which is mounted on the outer end of a rotatable shaft 26. The shaft 26 is journalled in a bearing 27 formed in the front face of the base 10. A gear 28 is mounted on the inner end of the shaft 26 which meshes with a rack bar 29 depending from the under side of the table 18. While a direct driving connection is provided between the hand wheel 25 and the rack bar 29, it will be readily apparent that a reduction gear mechanism, such as is old and well known in the art, may be employed, if desired. For a more complete disclosure of such a mechanism for traversing the work supporting table 18 either manually or by power, reference may be had to the expired U. S. patent to C. H. Norton, No. 762,838, dated June 14, 1904.

A wheel feeding mechanism is provided for manually feeding the grinding wheel 12 toward and from the work piece 22, which comprises a half nut 30 depending from the under side of the wheel slide 11. The half nut 30 meshes with or engages a rotatable cross feed screw 31. A forwardly extending portion 32 of the feed screw 31 is slidably keyed within a rotatable sleeve 33. The rotatable sleeve 33 is formed as an integral part of a rotatable shaft 34 which is supported in bearings 35 and 36 formed in the base 10 of the machine. A manually operable feed wheel 37 is mounted on the outer end of a stud 38. The stud 38 carries a pinion 39 which meshes with a gear 40 mounted on the outer end of the rotatable shaft 34 so that a manual rotation of the feed wheel 37 serves to rotate the feed screw 31 in either direction to cause a forward or rearward feeding movement of the grinding wheel 12 and its supporting wheel slide 11. The feed wheel 37

may be provided with a micrometer adjusting mechanism 41 which is substantially identical with that shown in the above-mentioned prior U. S. patent to Norton. This micrometer adjusting mechanism serves precisely to adjust a stop abutment relative to the manually operable infeed wheel 31 to compensate for wear of the grinding wheel and to facilitate setting up the machine for grinding work pieces to a predetermined size.

In the preferred construction the wheel slide 11 is arranged so that it may be moved toward and from the work piece 22 to grind the same to a predetermined size by means of a fluid pressure actuated grinding wheel feeding mechanism. As illustrated in the drawing, the rear end of the feed screw 31 is rotatably supported in a slidably keyed bearing 45 which is in turn supported in a casing 46 on the base 10 of the machine. A fluid pressure cylinder 47 is either attached to or formed integral with the casing 46 and contains a slidably mounted piston 48 which is connected by a piston rod 49 with the bearing member 45 and is arranged so that when fluid under pressure is admitted to a cylinder chamber 50, the piston 48 will be moved toward the right (Figs. 1 and 2), transmitting a corresponding movement through the feed screw 31 and the half nut 30 to move the wheel slide 11 and grinding wheel 12 rearwardly to an inoperative position. Similarly, when fluid under pressure is admitted to a cylinder chamber 51, a rapid approaching movement of the grinding wheel 12 and the wheel slide 11 will be obtained.

A fluid pressure system is provided to supply fluid under pressure for moving the piston 48 so as to cause a forward or rearward feeding movement of the grinding wheel 12. This system may comprise a reservoir 55 which is formed as a box-like section within the base 10 and serves to convey fluid under pressure through a pipe 56 to a motor driven fluid pressure pump 57. The pump 57 forces fluid under pressure through a pipe 58 to a control valve 59. The control valve 59 is preferably a piston type valve comprising a valve stem 60 having formed integrally therewith valve pistons 61, 62, 63 and 64. Fluid under pressure passing through the pipe 58 enters a valve chamber 65 (Fig. 2) located between the valve pistons 62 and 63 and passes through a passage 66 into the cylinder chamber 50 to move the piston 48 to its rearward position with the grinding wheel 12 separated from the work piece 22, as indicated in the drawing. During the rearward movement of the piston 48 toward the right (Figs. 1 and 2), fluid is exhausted from the cylinder chamber 51, through a passage 67, into a valve chamber 68 located between the valve pistons 61 and 62, and out through a pipe 69 which exhausts into the reservoir 60.

Similarly, when the valve stem 60 is shifted toward the left into its reverse position, fluid under pressure from the pump passing through the pipe 58 and entering the valve chamber 65 will pass through the passage 67 into the cylinder chamber 51 to cause a forward feeding movement of the wheel slide 11 and grinding wheel 12, that is, toward the left (Figs. 1 and 2). During the movement of the piston 48 toward the left, fluid within the cylinder chamber 50 passes out through the passage 68 into a valve chamber 70 located between the valve pistons 63 and 64 and passes out through a pipe 71 which connects with the pipe 69 and thereby exhausts fluid into the reservoir 55.

The valve stem 60 is arranged so that it may be moved endwise to shift the valve 59 into a reverse position so as to cause a forward or rearward feeding movement of the grinding wheel 12.

5 In the preferred form a manually operable control lever 80 is pivotally mounted on a stud 81 which is in turn supported by a bracket 82 fixedly mounted on the front of the machine base. A lever 82 is also pivotally mounted on the stud 81 and the lever 82 is fixedly mounted to move with the lever 80. The upper end of the lever 82 is provided with a stud 83 which engages a groove 84 formed in a spool-shaped member which is fixedly mounted on the forward end of the valve stem 60. It will be readily apparent from the foregoing disclosure that movement of the lever 80 in a counterclockwise direction will shift the valve 59 into the reverse position to initiate a forward feeding movement of the grinding wheel. Similarly, movement of the lever 80 into the position illustrated in Fig. 1 shifts the valve into its reverse position to cause a rearward separating movement of the grinding wheel 12 relative to the work piece 22.

25 As illustrated in the drawings, an electrically operated control mechanism is provided for shifting the valve 59 into its rearward position to cause a separating movement between the wheel and the work piece. A solenoid 85 is fixedly mounted within the machine base. The solenoid 85 is connected by means of a link 86 with the lever 82. When the solenoid 85 is energized, the valve 59 is automatically shifted into the position illustrated in Figs. 1 and 2. The energization of the solenoid 85 is controlled in a manner to be hereinafter described.

30 A fluid pressure controlled feed regulating mechanism is provided for modifying the rapid approaching movement caused by the piston 48 so as to produce the desired slow uniform in-feeding movement of the grinding wheel 12. In the preferred construction, a self-contained dash pot feed regulator is provided comprising a pair of dash pot cylinders 90 and 91 which contain 35 dash pot pistons 92 and 93, respectively. The dash pot pistons 92 and 93 and their respective cylinders 90 and 91 are arranged with their axes parallel to each other and spaced on diametrically opposite sides of the piston rod 49. The dash pot pistons 92 and 93 are normally held in a rearward (right-hand) position by means of springs 94 and 95, respectively. Adjustable stop screws 96 and 97 are provided to limit the rearward movement of the dash pot pistons 92 and 50 93, respectively. A slidable sleeve 98 is supported on the rearward end of the piston rod 49. The sleeve 98 is adjustably positioned on the rod 49, it being provided with an internally threaded portion which is screw threaded onto a reduced threaded portion 100 on the piston rod 49. A lock nut 101 is provided whereby the sleeve 98 may be readily locked in adjusted position.

55 The rapid forward feeding movement of the grinding wheel 12 and wheel slide 11 continues until the sleeve 98 on the threaded portion 100 of the piston rod 49 engages the right-hand end face of the dash pot pistons 92 and 93, respectively. Continued movement of the piston rod 49 moves the sleeve 98 and continued movement 60 serves to move the dash pot pistons 92 and 93 in a direction toward the left, so as to reduce the rapid approaching movement of the grinding wheel 12 toward the work piece 22 to a slower but predetermined grinding feed due to the fact 65 that fluid confined within the dash pot cylinders 70 75

90 and 91, respectively, must exhaust through a restricted aperture to be hereinafter described. The dash pot cylinders 90 and 91 are interconnected by a passage 102. Fluid confined within the dash pot cylinders 90 and 91 must exhaust through a passage 103, a needle valve 104, and through a passage 105, into a fluid reservoir 106. By adjusting the aperture of the needle valve 104, a desired and predetermined infeeding movement of the grinding wheel 12 may be obtained.

When fluid under pressure is admitted to the cylinder chamber 50 to cause a rearward movement of the piston 48, the sleeve 98 is also moved rearwardly so as to release the compression of the springs 94 and 95, respectively, which returns the dash pot pistons 92 and 93, respectively, to their rearward position (Figs. 1 and 2). The rearward movement of the dash pot pistons 92 and 93 is limited by the adjustment of the stop screws 96 and 97, respectively. During the rearward movement of the dash pot pistons 92 and 93, a suction is created within the dash pot cylinders 90 and 91, respectively, which serves to aid in drawing fluid from the reservoir 106, through a pipe 107 and a ball check valve 108, rapidly to fill the dash pot cylinder chambers 90 and 91 for the next infeeding movement of the grinding wheel 12. During the infeeding movement of the dash pot pistons 92 and 93, fluid within the dash pot cylinders 90 and 91, respectively, serves to hold the ball check valve 108 closed so that fluid within the dash pot cylinders 90 and 91 is forced out through the passage 103 and the needle valve 104, into the reservoir 106, to control the rate of infeeding movement as desired.

The forward feeding movement of the grinding wheel 12 as controlled by the dash pot pistons 92 and 93, respectively, continues until an adjustable stop collar 109 carried by the sleeve 98 engages a fixed stop surface 110 on the rear face of the dash pot cylinder head. A pair of locking collars 111 serve to maintain the stop collar 109 in adjusted position.

In order to obtain a finish grinding operation with the grinding wheel 12 held immovable in its forward position, it is desirable to provide a suitable control mechanism whereby the grinding wheel may be maintained in its foremost position for a predetermined time interval. In the preferred construction, an adjustable electrical time delay relay 115 is so connected as to regulate and control the shifting movement of the feed control valve 59 so as to control the extent of the finish grinding operation. A normally open limit switch 116 is supported on a bracket 117 on the rear of the feeding mechanism. A detent 118 carried by one of the collars 111 is positioned in the path of an actuating roller 119 on the limit switch 116. The limit switch 116 is adjustably positioned on the bracket 117 so that it may be adjusted in such a position that the detent 118 will engage the roller 119 and close the switch 116 when the sleeve 109 moves into engagement with the stop surface 110. When the limit switch 116 closes, it sets the time relay 115 in motion and the grinding operation continues for a predetermined time interval according to the setting of the time relay, after which the time relay operates to close a circuit and energize the solenoid 85. Closing of the solenoid 85 shifts the control valve 59 into its reverse position to admit fluid under pressure from the pipe 58 into the valve chamber 65 and through the passage 66 into the cylinder chamber 50 to cause a rearward movement of the piston

48, thus separating the grinding wheel 12 from operative engagement with the work piece 22. By adjustment of the time relay 115, the dwell period of finish grinding on the work piece 22 may be varied as desired.

In order to eliminate the effect of any backlash in the feeding mechanism parts, a mechanism is provided for applying a definite and predetermined pressure on the wheel slide 11. In the feeding mechanism shown in the drawing, a mechanism has been provided for applying a constant and predetermined pressure or pull on the wheel slide 11 in a rearward direction so that the thrust of the feed screw 31 together with the piston 48 is always in a given direction and any lost motion or backlash between the nut 30 and the screw 31 together with the slidable bearing member 45 is thus taken up always in the same direction. In the preferred form a fluid pressure operated mechanism is provided comprising a fluid pressure cylinder 120 which contains a slidably mounted piston 121. The cylinder 120 is adjustably supported by a bracket 122 which is fixed on the rear of the wheel feeding mechanism. The upper end of the bracket 122 is provided with a cylindrical aperture 123 within which the cylinder 120 fits. The upper part of the bracket 120 is slotted and the two spaced parts thereof provided with clamping or binder screws 124 and 125 by means of which the cylinder 120 may be readily clamped in adjusted position in fixed relationship with the bracket 22. This adjustment between the cylinder 120 and the bracket 122 is provided to facilitate setting up the machine for grinding work pieces of different diameters.

A piston rod 126 is connected at one end to the piston 121. The other end of the piston rod 126 is connected by means of a bracket 127 with the rear face of the wheel slide 11. A pipe 128 is connected to the pipe 58 so as to receive direct pressure from the pump 57 and admit fluid under pressure to a cylinder chamber 129 so that at all times during the operation of the feeding mechanism, fluid pressure is applied to the piston 121 tending to move it in a direction toward the right, thus pulling back in a rearward direction on the wheel slide 11 so that the thrust of the feeding mechanism parts is always in a rearward direction during the forward or rearward movement of the wheel slide. An adjustable valve 134 is provided in the pipe line 128 by means of which the passage of fluid under pressure through the pipe 128 may be varied as desired.

A pressure relief valve 130 is connected by a pipe 131 with the pressure pipe 58 and serves to maintain a predetermined fluid pressure within the fluid pressure system. If for any reason the pressure within the system increases over the set pressure, the relief valve 130 automatically opens and by-passes excess fluid under pressure through a pipe 132 into the reservoir 55. It will be readily apparent from the foregoing disclosure that by applying a definite and predetermined rearward pressure to the wheel slide 11 during both its forward and rearward feeding movements, the wheel slide 11 is accurately controlled so that it may be precisely fed into a predetermined stopped position accurately to control the size of successive work pieces 22.

The operation of this improved wheel feed controlling mechanism will be readily apparent from the foregoing disclosure. A work piece 22 is set in position on the headstock and footstock members.

Assuming all of the feed adjustments have been made, the operator shifts the lever 80 in a counterclockwise direction to reverse the feed control valve 59 so that fluid under pressure from the pipe 58 is admitted through the passage 67 into the cylinder chamber 51 to initiate a forward infeeding movement of the grinding wheel 12. At the same time, fluid under pressure passes through the valve 134 which has previously been adjusted, into the cylinder chamber 129 to maintain the desired and predetermined back pressure on the wheel slide 11 during the infeeding movement, thus providing a precisely controlled infeeding movement whereby duplicate work pieces within fine limits may be successively produced.

The infeeding movement of the grinding wheel 12 continues as a rapid approaching movement as governed by the movement of the piston 48 until the collar 98 engages and picks up the dash pots 92 and 93, after which the rapid approaching movement is reduced to a slow, uniform, controlled grinding feed which continues until the stop sleeve 109 engages the stop surface 110 to limit the forward advancing movement of the grinding wheel 12. As the sleeve 109 engages the stop surface 110, the detent 118 engages the roller 119 and closes the limit switch 116, which sets in motion the time relay 115, which governs the extent of the finish grinding operation. After the predetermined set interval, the time relay 115 operates to close the circuit, thereby energizing the solenoid 85, which rapidly shifts the valve stem 60 toward the left to reverse the position of the valve 59, thereby admitting fluid under pressure into the cylinder chamber 50 to cause a rearward movement of the wheel slide 11 and grinding wheel 12.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in

the accompanying drawing is to be interpreted as illustrative and not in a limiting sense.

I claim:

1. In a grinding machine having a rotatable grinding wheel, a transversely movable slide therefor, a hydraulically operated mechanism including a piston and cylinder operatively connected to move said slide transversely in either direction to produce either a forward or rearward feeding movement of the grinding wheel, a fluid pressure system including a fluid pump to supply fluid under pressure to said cylinder, a feed control valve therefor, a second piston and cylinder, means operatively connecting said piston with said slide, a bracket fixedly mounted relative to the base, an adjustable clamping device on said bracket adjustably to support said cylinder, and fluid connections between said pump and said second cylinder continuously to exert a thrust on said slide in one direction during the forward and rearward feeding movement of the slide to eliminate backlash in said feeding mechanism.
2. In a grinding machine having a rotatable grinding wheel, a transversely movable slide therefor, a feeding mechanism including a nut and screw operatively connected to move said slide transversely, a hydraulically operated mechanism including a piston and cylinder operatively connected to move said screw axially in either direction to produce either a forward or rearward feeding movement of the grinding wheel, a fluid pressure system including a fluid pump to supply fluid under pressure to said cylinder, a feed control valve therefor, a second piston and cylinder, means operatively connecting said piston with said slide, a bracket fixedly mounted on the rear of the base, a cylindrical bore in said bracket to fit the periphery of said second cylinder, means to clamp said cylinder in adjusted position relative to said bracket, and fluid connections between said pump and said second cylinder continuously to exert a thrust on said slide in one direction during the forward and rearward feeding movement of the slide to eliminate backlash in said feeding mechanism.

HERBERT A. SILVEN.
